E. B. WILLIAMS

HANGER OR SINGLETREE

Filed Aug. 14, 1926

Patented Jan. 3, 1928.

1,655,301

UNITED STATES PATENT OFFICE.

EDWARD BEST WILLIAMS, OF CORNELIA, GEORGIA, ASSIGNOR OF ONE-HALF TO
THERESA LOU RAMEY, OF CORNELIA, GEORGIA.

HANGER OR SINGLETREE.

Application filed August 14, 1926. Serial No. 129,244.

This invention relates to devices designed to be used as singletrees, as a hanger for supporting hogs when hogs are killed, or as a wagon tongue neck yoke.

5 The general object of the invention is to provide a device of this nature having a body formed with hooks at its ends and to provide hook closing levers pivotally mounted upon the body, and means whereby the 10 hook closing levers may be pulled to close the hooks when strain is applied to the body or to the levers.

A further object is to provide a device of this character which is so constructed that 15 any elements engaged with the hooks will be held from accidental removal from the hooks by strain applied to the body.

A still further object is to provide a device of this character whose principle may 20 be applied to singletrees, to neck yokes, or to butchers' gambrels.

Other objects will appear in the course of the following description.

My invention is illustrated in the accompanying drawings wherein:—

Figure 1 is a top plan view of my device when used as a singletree;

Fig. 2 is a view similar to Figure 1 but partially in section as indicated, and showing the hooks open.

Fig. 3 is a top plan view of a wagon tongue with my device applied thereto;

Fig. 4 is a front elevation of my device when used as a wagon neck yoke.

35 Referring to these drawings 10 designates a body which is relatively elongated and is relatively narrow and is cut out at its ends to provide two hook portions 11. Pivot to the body are the levers 12 which embrace the 40 body and have the outer end portions thereof disposed within the hooks 11. To the inner ends of these levers 12 are connected the two upwardly converging pairs of links 13 which are pivoted at 14 to the lower ends 45 of the levers 12 and are at their other ends connected by the pivot bolt 15. A supporting ring or shackle 16 is engaged by this pivot bolt.

Assuming that the ring 16 is engaged 50 with a support and objects be hung upon the hooks 11, then the weight of these objects on the body will cause the body to move downward relative to the links 13 and this will pull upward on the inner ends of the 55 levers 12 causing the outer ends of the

levers to move downward against the extremities of the hooks 11, thus closing the gap of the hooks and locking any object to the hooks. Upon a release of this strain, the body may be moved toward the pivot 60 bolt 15 to thus cause the shifting of the levers.

The principle of this device may be applied to a number of different uses. Thus, the device may be used as a singletree in 65 which case the pivot bolt 15 may connect the singletree to the wagon tongue and the draft devices of the two horses will be connected to the hooks 11. On the other hand, the device may be used for supporting hogs 70 while they are being dressed after killing, in which case the ring 16 will be supported from a suitable overhead structure and the hogs may be hung up by chains to the hooks 11. It may also be used as a wagon neck 75 yoke as illustrated in Figure 4. In this case, the ring 16 will be slipped over the end of the wagon tongue and the straps 17 will engage with the hooks 11. In any case the strain upon the body and links will cause 80 the levers to close and thus lock the object within the hooks 11 and there will be no danger of this object, as for instance a ring, or the end of a draft chain, coming loose. It will be obvious that this device is capable 85 of many applications on a farm or under other circumstances.

I claim:—

A tree structure comprising a bar provided in the vicinity of its ends and at the 90 same side edge with recesses forming hooks, the end surfaces of the said hooks being located between the planes of the longitudinal edges of the bar, lever members pivoted at the side of the bar and adapted to bridge 95 the recesses and having end portions engageable with the ends of the hooks, said levers when engaging the hooks lying completely between the planes of the longitudinal edges of the bar, link members pivotally connected with the inner ends of the levers, the combined lengths of the link members being greater than the distance between the inner 100 ends of the levers when said levers are in engagement with the hooks and said link members having their inner ends pivotally connected together.

In testimony whereof I hereunto affix my signature.

EDWARD BEST WILLIAMS.
